RAIL BOND

Edward M. Deems, Forest Hills, N. Y., assignor to
 Railroad Accessories Corporation, New York,
 N. Y., a corporation of New York

Application March 28, 1935, Serial No. 13,389

1 Claim. (Cl. 173—280)

This invention relates to conductors, more especially to conductors for connecting the adjacent ends of railway rails, particularly those for use in connection with railway track circuits.

It is well understood by those skilled in the railway signalling art, that a track circuit includes an insulated section of the trackway formed by placing insulating joints in each of the lines of rails, and by connecting a battery across the rails at one end, and a relay across the rails at the other end.

It is also well understood that the ordinary rail connecting or fish plates connecting the adjacent ends of the ordinary thirty-six foot sections are not to be relied upon to furnish sufficient conductivity for the electrical energy which flows in the rails from the battery at one end of the section to the relay at the other end thereof. This fact has necessitated a special bonding of each of the adjacent butting rail ends within the section.

Great difficulties have been encountered in successfully bonding the adjacent abutting rail ends in track circuit sections because provision has to be made for many adverse conditions. A common method is to bond, from one rail web to the adjacent rail web by means of one or a plurality of conductors of a length somewhat greater than the length of the fish plates. This method of bonding exposes the bonding wires to mechanical injury, in that they may become entangled with dragging parts from the rolling stock, or may actually get onto the top of the rail, and so be severed by the passage thereover of the wheels of rolling stock. In addition, they are very likely to be damaged by track men while working along the track, particularly when working in and about the rail joint, and more especially when tightening the bolts thereof, or replacing the fish plates with new plates.

A very pronounced difficulty with the old type of bond is, that due to its length and in spite of its size as it may be commercially used, it does not offer a conductivity as great as is desired. The desired conductivity cannot be attained without enlarging the bond to a prohibitive extent.

Attempts have been made to increase the conductivity and decrease the mechanical disadvantages of bonds by applying a bond directly to the rail heads. Such a bond can be very short, as compared with the previously described bond. Therefore, for a given diameter it has an increased conductivity. Such bonds have, in general, been applied to the head of the rail by elec-

trical or flame welding. Many competent engineers are adverse to applying any considerable degree of heat to the side of the ball of a rail, especially adjacent the end thereof, and this reluctance, considered by many to be well founded, has militated against the use of such bonds.

A further difficulty which has been met with in the type of bond applied directly to the rail heads is that it is particularly exposed to injury by snow ploughs and ballast spreaders. Both of these devices, and especially the ballast spreader, have parts which extend below the top surface of the head of the rail on the outside thereof. These parts, due to the swaying of the vehicle, come in contact with the head of rail bonds and destroy them.

Attempts have been made to attach bonds to rail heads by drilling a cavity in the rail head and attaching the bond to a plug driven into the cavity. A difficulty with this type of bond arises from the fact that it is necessary to drill a relatively deep hole in the head of the rail. This hole penetrated what might be called the active cross-sectional area of the head and to that extent weakened the rail head.

In my copending application Serial No. 538,943, now Patent No. 2,045,126, filed May 21, 1931, I have illustrated, described and claimed a type of bond for attachment to rail heads. This type of bond obviates many of the defects of the type of bond heretofore used and has many desirable virtues especially in that the cavity which must be formed in the head of the rail for the reception thereof is so shallow that it does not penetrate the active load-sustaining cross-section of the rail. By reason of this fact incipient cracks which may develop in the rail head are not afforded an easy opportunity to spread by reason of the cavity formed for the reception of the head of the rail bond, as that cavity does not closely approach the point of origin of the cracks.

I have discovered, in practice, that the type of bond illustrated and described in my copending application, hereinbefore referred to, has a weakness in that it is subject to injury at the junction line of the surface in which the cavity is produced and the bond.

A principal object of this invention is to provide a bond of the type illustrated, described, and claimed in my copending application hereinbefore mentioned, of such construction that any tendency towards mutilation of the bond at the line of contact between the bond and the edge of the cavity in the rail head will be obviated.

In my Letters Patent No. 1,945,480, I have

illustrated, described and claimed a method of connecting an end of a rail bond to a rail which consists in attaching an electrical conductor conductively to a contacting member having a portion bearing against the inside surface of such a shallow rail cavity as that above mentioned and then exerting pressure in such a manner that only that portion of the contacting member within the cavity has force exerted thereagainst, whereby fracture of the contacting member along the line of juncture of the contacting body and the edge of the cavity is avoided.

In that patent the particular illustrative embodiment of the method disclosed comprised a conducting member having a body part or parts which filled the entire cavity and approximated in diameter that of the adjacent edge of the cavity.

An object of the present invention is to provide an improvement in a rail bond made according to the said method and which relates to a type of bond in which a stranded conductor is employed of considerably less diameter than that of the cavity in the body to which the conductor is to be attached.

Other objects and advantages will appear as the description of the particular physical embodiments selected to illustrate the invention progresses and the novel features will be particularly pointed out in the appended claim.

In describing the invention in detail and the particular physical embodiments selected to illustrate the invention, reference will be had to the accompanying drawing and the several views thereon, in which similar parts will be designated by similar characters throughout the several views, and in which:

Figure 1 is a fragmentary vertical sectional view of a portion of rail head with a portion of a bond embodying my invention in place therein; Fig. 2 is a fragmentary view illustrating a side elevation of the arrangement as shown by Fig. 1; Fig. 3 is a part section, part elevation taken on the line III-III of Fig. 1, looking in the direction indicated by the arrows; Fig. 4 is a view similar to Fig. 3 but illustrating the initial position of the plug portion of my bond as it is being driven into a cavity in a rail head; Fig. 5 is a side elevational view showing the parts in the position illustrated by Fig. 4; Fig. 6 is a view similar to Fig. 4 but showing a modified form of bond; Fig. 7 is a view similar to Fig. 3 but showing the form of bond illustrated in Fig. 6; Fig. 8 is a side elevational view similar to Fig. 2, 55 of the plug as illustrated by Fig. 7 but taken separately; Fig. 9 is a view corresponding to Fig. 4 but showing a modified form of bond as illustrated by Fig. 13 and Fig. 14; Fig. 10 is a view corresponding to Fig. 5 but showing the form of bond illustrated in Fig. 13; Fig. 11 is a view corresponding to Fig. 3 but illustrating the bond of Fig. 10; Fig. 12 is a cross-sectional view of the bond as shown by Fig. 10 but in a plane defined by the line XII-XII and viewed in the 65 direction indicated by the arrows at the ends of the line; Fig. 13 is a detail view in end elevation of the plug shown in Figs. 9 and 10, in its original condition; Fig. 14 is a view thereof in side elevation.

In Fig. 1 is a fragment of a rail head 1 is shown. This rail head, as shown in Fig. 1, has a cavity 2 formed therein, by using the usual form of drill of a predetermined gauge. The cavity is so shallow preferably as to lie entirely without, 75 or substantially entirely without, what might be

called the active cross-section of the rail, that is, that portion of the cross-section of the rail least active in sustaining the stresses of the passing train. To this end applicant not only forms the cavity 2 very shallow, but also forms the cavity 5 well down upon the side of the head of the rail, as most clearly shown in Fig. 1.

The conductor portion of the bond is made of any suitable electrical conducting material. Applicant prefers to make the bond of a copper 10 strand or cable as 2, of conventional or suitable structure and dimensions, within the range of sizes which the cavity is adapted to receive.

In order to attach the end or terminal portion of the conductor to the body of metal comprising the rail head 1, and in which is formed the cavity 2, as already described, applicant employs a plug, as 4, which may be assembled loosely with the conductor terminal end portion and introduced into the cavity 2 as indicated in Fig. 20 4. It will be observed from the latter figure that the assembled portions of the plug 4 and conductor 3 have an aggregate bulk less than that of the capacity of the cavity 2. Accordingly there will never be under any conditions a protrusion 25 of the plug material beyond the edge of the cavity, and so there can be no danger of the cable being injured or sheared off across that edge. It therefore will retain its integrity at all times.

The plug 4 is of any suitable conductive metal, 30 somewhat plastic, so that it can be deformed by pressure applied with a suitable tool, and when so deformed, as into the position shown in Fig. 1, and more clearly in Fig. 3, the material of the plug is flowed laterally into firm mechanical and 35 electrical contact with the inner walls of the cavity 2 as at 5, and similarly into the conical concavity 6 at the inner end of the cavity 2. At the same time the plug metal is flowed into the interstices between the strand components as 40 at 7, and the strand is compressed between the wall 5 of the cavity and the opposed margin 7 of the plug.

To facilitate the assembly of the conductor and plug and their simultaneous introduction into the cavity, the plug may have a marginal channel, groove or recess, as 8 (see Fig. 5), and the plug may also have its leading end bevelled, as at 9, this furthering the deformation of the plug 50 at its nose against the contiguous bottom wall of the cavity, and also facilitating the flowing of the plug material into and around the end of the strand 3 and thus promoting the highly efficient electrical connection which is the prime requisite of every efficient rail bond.

In its completed condition the plug is shortened somewhat in length so that it occupies a final position remote from the edge 10 of the cavity, and there can be no shearing action at that region, either of the plug, or of the conductor 3, 60 as the latter is maintained in a freely flexible condition and can be flexed without undue tendency to break down. Being flexible, it is better capable of accommodating itself to casual blows, pulls, and other strains, and as it is firmly anchored by 65 the plug, it is only displaced with desirable difficulty. The plug itself and the union between the plug 4, conductor terminal 3 and ball of the rail, is completely secluded within the cavity 2 and protected by the walls thereof, so that its life 70 is substantially equal to that of the associated metal parts.

The intended and highly desirable advantages above recited and secured by provision of the plug and conductor union illustrated in Figs. 1 to 5 75

inclusive and described with reference to the form therein shown, may be likewise secured by modified forms of plugs.

One such modification is illustrated in Figs. 6, 5 7, and 8, which show a plug 12 of the same general shape as that described with reference to Figs. 1 to 5, but in this form of plug a co-axially disposed orifice 13 takes the place of the marginal groove or recess 8 of the form shown in Fig. 5, 10 etc. This form has some advantages in operation, among which may be noted the ease with which it may be secured to the strand 14 before the introduction of the assembly to a cavity. The bonds may have their appropriate plugs secured to the ends at a remote place of manufacture, and, so equipped, be shipped ready for use, a thoroughly desirable capability, as will be recognized by those skilled in the art.

In so stating this advantage, as particularly 20 characteristic of the form of plug shown in Figs. 6, 7 and 8, it is not intended to exclude the possibility of so deforming the structure of plug 4 as to secure a like advantage, and in general this attachment of any like plug to its conductor may 25 be effected in any analogous manner.

In Figs. 9 to 14 inclusive is illustrated another modification of plug adapted to carry into effect the novel method of annexing one end of a bond to a body of metal, such as the ball of a rail.

30 In this modification the plug has a body 16 of lozenge shape, and a conical leading end 17. The sides of the body are formed with grooves or recesses 18 at diametrically opposite margins, and the nose is grooved with a channel 19 connecting the grooves 18, the grooving therefore taking the form of a U-shaped channel adapted to receive the bight or loop 21 at the terminal end of a strand conductor, as at 20, in Figs. 9-12.

It can easily be seen that all of the advantages already detailed are presented par excellence, in this form of embodiment of the invention. The contacts for electrical union are tripled in area, approximately, the possibility of displacement from the rail is of minimum character; and by simply twisting together the end portions 22 and 23, around the plug enclosed in the loop 20, the plug can be retained in its assembled relation with the conductor, from the place of manufacture to the site of intended use.

5 Although I have particularly described one particular physical embodiment of my invention and explained the operation, construction and principle thereof, nevertheless, I desire to have it 15 understood that the form selected is merely illustrative, but does not exhaust the possible physical embodiments of the idea of means underlying my invention.

20 What I claim as new and desire to secure by Letters Patent of the United States, is:

The method of affixing one end of a stranded rail bond conductor to the ball of a rail having a shallow cavity formed therein, which consists 25 in the step of assembling a terminal portion of said stranded conductor with a plug of substantially plastic metal, said assembly having an aggregate bulk less than the stereometric capacity of said cavity, the step of introducing said assembly to the cavity, and the step of exerting pressure 30 against said plug in such a manner as to flow the metal of said plug into the interstices of said stranded conductor and directly against the end and side inner walls of said cavity.
